LENS POLISHING MACHINE

Lowell L. Houchin, Columbus, Ohio

Application June 18, 1935, Serial No. 27,216

5 Claims. (Cl. 51—263)

My invention relates to a lens polishing machine. It has to do, more particularly, with a lens polishing machine which is provided with means for automatically feeding the rouge or polishing material upon the lens grinding lap and which is further provided with special means for mounting the lens grinding lap or tool on the machine. However, these features are not necessarily limited in their application to a machine for polishing lenses.

It is now customary in the art to apply the rouge to the lap by dipping a brush in the rouge disposed in the pan which surrounds the lap and then use the brush to apply the rouge to the lap. Obviously, with this method it is necessary for the operator to constantly inspect the lap and keep a supply of rouge thereon. Attempts have been made to eliminate the necessity of constant inspection by the operator and the dependence upon the operator to see that sufficient rouge is always on the lap.

It has been proposed to provide some means for automatically feeding the rouge on the lap. One of the prior art devices employed for this purpose embodies a curled spoon which is placed in the pan surrounding the lap and which is adapted to pick up the rouge and throw it on the lap. However, this device has not proved practicable and the method commonly used in the art at the present time, is to employ a brush for applying the rouge, as stated above. In prior art machines, it is common to have a pan that receives the polishing material and have the lap disposed within the pan and mounted on a tapered spindle projecting up through the bottom of the pan. With this structure, a concave tool would project upwardly a much greater distance than a convex tool because on a convex tool the depending boss, which fitted over the tapered spindle, would be disposed partly up within the concavity formed in the lower surface thereof, which will be clear to one familiar with the art. Consequently, if a machine were provided with a curled spoon for feeding the rouge on the lap or tool, as described above, each time a convex tool was removed and replaced with a concave tool or vice versa, the vertical position of the spoon would also have to be varied. Also, because the tool is mounted on the spindle as indicated, it is necessary to have a pan with comparatively high side walls in order that they will extend above the top of the tool or lap even when it is a concave tool. The rouge feeding device embodying the curled spoon has had a number of

other undesirable features and has not worked satisfactorily at all.

It has been found that the manner in which the tool or lap is mounted on the machine, as described above, is not entirely satisfactory. As 5 previously stated, the highest point of the concave and convex tools or laps will be at various points, if the tool is mounted on the spindle as described above. Another disadvantage of this mounting for the tool resides in the fact that it is 10 necessary to employ hooks to pull the tool from the spindle because the tapered chuck fits so tightly on the tapered spindle. Thus, it is difficult to remove the tool or lap. This mounting for the tool or lap has other disadvantages.

One of the objects of my invention is to provide 15 a lens polishing machine which is provided with means for automatically and efficiently feeding the rouge on the lap which eliminates the necessity of constant inspection by the operator.

Another object of my invention is to provide 20 novel means for mounting the lap or tool on the machine which has a number of advantages in itself but which also cooperates with the automatic rouge feeding device in a special manner.

In its preferred form my invention contemplates the provision of a machine of the type indicated having a tapered spindle and having a pan with a tapered chuck adapted to cooperate therewith. Thus, the pan itself is mounted directly 25 on the spindle and the lap or tool is not mounted on the spindle as in prior art machines. Instead, the lap or tool is mounted directly on the pan itself. The lap or tool is of special construction and rests on the bottom of the pan. 30 It is secured in position by means of an eccentric or cam lock.

The machine is further provided with a device 35 which automatically picks up the rouge material and applies it to the face of the lap or tool. 40 This device is of such a nature that it will work very efficiently and keep a constant supply of rouge on the face of the lap. It is provided with a valve by means of which the amount of rouge supplied to the lap may be controlled. It may be 45 adjusted to the proper height within the pan and held in adjusted position. Because of the particular mounting for the lap or tool and the structure of such lap or tool, the vertical position of the automatic rouge feeding device need 50 not be changed when a convex tool is replaced by a concave tool and vice versa. The highest point of the concave tool will be at substantially the same location as the highest point of a convex tool. Consequently, the pan need not have 55

side walls nearly so high as the side walls of pans of prior art machines.

The preferred embodiment of my invention is illustrated in the accompanying drawings where-
5 in similar characters of reference designate cor-
responding parts and wherein:

Figure 1 is a perspective view, partly broken away, of a lens polishing machine provided with the automatic rouge feeding device and with a
10 lap mounted thereon by the special means which I have provided.

Figure 2 is a plan view showing the automatic rouge feeding device in position within the pan.

Figure 3 is a vertical section taken through the
15 pan and illustrating the rouge feeding device positioned therein and the means for mounting the lap within the pan.

Figure 4 is a horizontal section taken substantially on line 4—4 of Figure 3.

20 Figure 5 is a vertical section taken through the main portion of the rouge feeding device.

Figure 6 is a horizontal section taken substantially on line 6—6 of Figure 5.

With reference to the drawings, I have illus-
25 trated my invention in Figure 1 as being applied to a lens polishing machine part of which is disclosed in this figure. However, it will be apparent that my invention is applicable to other types of polishing machines and is not limited to polishing machines but may be applied to grinding ma-
30 chines and other similar machines.

The machine illustrated is provided with a forwardly extending arm 1 having an adjustable depending rod 2 at its outer end which has a lens blank carrier 3 mounted on its lower end. This lens blank carrier 3 will have a lens blank 4 mounted thereon which contacts with the upper surface of a lens polishing lap 5, which is mounted on the machine in a manner to be described
35 hereinafter. Spring and rod mechanism 6 is provided for exerting a downward force on the arm 1 which is pivoted in a suitable manner (not shown) to permit downward movement of the outer end thereof. Also, means is provided which
40 is not shown for causing the arm 1 to move laterally in the usual manner.

I will now describe how the lap 5 is mounted on the machine. This mounting is shown best in Figures 3 and 4. As shown, the machine is pro-
50 vided with a spindle 7 in the usual manner which is rotated by suitable mechanism. The upper end of this spindle is tapered in the usual way. A pan 8 is provided with a tapered chuck 9 located centrally in its bottom which is adapted
55 to receive the upper end of the spindle 7. Thus the pan may be removably mounted on the spindle merely by passing the upper end of the spindle into the chuck.

The pan 8 is of special construction. It is pref-
60 erably made of metal and is mainly of cylindrical form. It has a side wall 10 which extends upwardly a suitable distance. At the upper end of the side wall an inwardly extending inclined peripher-
65 al flange 11 is formed thereon. This flange is provided for preventing the rouge or polishing material from passing over the upper edge of the side wall 10. The pan is provided with a bottom which is substantially flat. However, it is provided with a slightly raised central portion
70 12. Surrounding this raised portion is a trough-
like portion 13 adjacent the periphery of the pan. The pan 10 is adapted to receive the rouge or polishing material which embodies a suitable powder mixed with a suitable liquid so that it will be in the form of a thick fluid. This ma-

terial will normally lie in the trough-like portion 13. A socket 14 is formed centrally within the raised portion 12 of the bottom. At the periphery of this socket a smaller socket 15 is formed. This socket 15 has an eccentrically mounted disk 16 disposed therein which is of less diameter than the socket. This disk 16 is eccentrically mounted on the upper end of a shaft 17 which is mounted for rotation in the bottom of the pan and projects downwardly through such bottom. This shaft 17 has an outwardly extending pin 18 on its lower end to facilitate rotation thereof. The shaft 17 may be rotated to cause the eccentric 16 to project within the circumference of the socket 14 or to lie outside such circumference. 15

The tool or lap 5 which I employ with this machine is of special construction. As shown, it comprises a main body portion having a downwardly extending flange 19 at its outer edge. It also has a concentrically disposed down-
20 wardly extending annular flange 20. The flange 20 is adapted to be inserted in the socket 14 and, consequently, projects downwardly a greater distance than the flange 19. However, the flange 20 is of such size as to permit the flange 19 to contact with the bottom of the pan. Consequently, there will be no danger of the polishing material or other abrasive material passing inwardly past this flange 19 and reaching the mechanism used for mounting the lap on the pan. 30

In mounting the lap in the pan, the shaft 17 is rotated by the pin 18 which may be reached from a point beneath the pan until the eccentric 16 lies outside of the socket 14. This will permit insertion of the annular flange 20 within the 35 socket 14. The shaft 17 may then be rotated to cause the eccentric 16 to engage the flange 20 and thereby securely hold the flange within the socket 14. Thus, the lap 5 will be securely mounted on the bottom of the pan. It may be readily 40 removed merely by rotating the shaft 17 which will permit withdrawal of the flange 20 from the socket 14. The lap 5 is provided with a central hollow space (Figure 3) to eliminate any danger of the upper end of the spindle 7 contacting with 45 the lap.

With this structure for mounting the lap on the machine and the particular lap structure, the lap may be readily removed and replaced when-
50 ever desired. No hooks will be necessary in order to be able to remove the lap. The eccentric lock may be readily operated to permit free removal of the lap. Furthermore, the highest point of the lap will always be at substantially the same point regardless of whether the lap is convex or con-
55 cave. Consequently, the side wall 10 of the pan need not extend upwardly nearly as high as the side walls of the pans used in prior art machines. This also is due to the fact that the lap rests di-
rectly on the bottom of the pan. 60

I will now describe the automatic rouge feed-
65 ing device which I have provided. As shown in Figure 1, the machine is provided with a forwardly extending rod 22 which has its rear end secured to a suitable immovable support on the machine. This rod 22 extends forwardly into substantially tangential relation to the side wall of the pan 8. The forward end of the rod 22 passes through an opening formed in a sleeve 70 23. The sleeve 23 may be adjusted along the rod and may be held in adjusted position by means of a set screw 24. The upper end of a vertically disposed rod 25 passes through an opening in the other end of the sleeve 23. The upper end of this 75

rod 25 is threaded and a nut 26 is threaded thereon above the sleeve 23. By rotating this nut 26, the rod 25 may be moved up and down. It may be held in adjusted position by a setscrew 5 similar to the setscrew 24 threaded into the upper end of the sleeve.

The rod 25 extends downwardly into the pan 8. It carries on its lower end a member 27 which is adapted to gather in the polishing material when the pan 8 rotates. It will be apparent that when the pan rotates, the polishing material is thrown outwardly against the side wall 10 thereof by means of centrifugal force and is carried along with the pan. This member 27 is so shaped that it will scoop in a portion of this polishing material. The lower end of the rod 25 may be rigidly secured to the member 27 by means of screws 28 as indicated in Figure 3. The member 27 is so located that it will lie closely adjacent the inner surface of the side wall 10.

The shape of this member 27 is very important. As shown in the drawings, it has a substantially straight inner side wall 29 and a curved outer side wall 30 of substantially the same curvature as the side wall 10 of the pan so that it may lie closely adjacent the side wall of the pan. The side walls 29 and 30 are spaced apart to form a chamber 31 therebetween. This chamber is wider at its rear end than it is at its forward end as illustrated best in Figure 6. Furthermore, as illustrated in Figure 5, the bottom 32 of this chamber is inclined forwardly and upwardly. The top is closed by a substantially flat wall 33. The forward end of the chamber 31 is closed by a wall 34. Thus, this chamber 31 is of substantially large cross section at its rear end but decreases in cross section towards its forward end and at its forward end is of comparatively small cross sectional area. The rear end of the chamber 31 is almost closed by a transverse wall 35. However, adjacent the wall 30 there is provided a narrow slot 36 formed in the wall 35.

The side wall 29 is continued rearwardly past the transverse wall 35 a substantial distance, as illustrated at 37. The top wall 33 is continued rearwardly in a similar manner. These two walls cooperate to form a pocket 39 at the rear of the member 27 and behind the wall 35. The side wall 30, however, terminates at the point where the wall 35 is formed. The bottom wall 32 has a portion 40 projecting rearwardly to a slight extent past the wall 35. However, this portion 40 is cut away at a point directly below the slot 36. It is important to have this pocket formed at the rear end of the member 27, as described.

The forward end of the chamber 31 has an outlet opening 41 formed in the side wall 29 into which the inner end of a tube 42 is threaded. In the outer end of this tube 42, a valve 43 is provided for controlling the amount of polishing material which will pass through the tube 42. This valve merely embodies a pin which has a transverse opening 44 that may be brought exactly into coincidence with the passage 45 in the tube 42 or out of coincidence with such passage, merely by rotating the pin. With this valve the amount of material passing through the tube 42 may be controlled or completely prevented. The outer end of the tube 42 has a flexible tube 46 suitably mounted thereon. This tube is preferably made of rubber. It extends over the lap and will feed the polishing material onto the lap. Since it is made of rubber, there will be no

danger of injuring the lap even if it contacts therewith.

In using this automatic rouge feeding device, the sleeve 23 is adjusted along the rod 22 and the rod 25 is properly adjusted vertically in the sleeve 23, in order that the member 27 will be properly positioned within the pan. As shown in Figure 3, the lower edge of the member 27 is preferably at a point just at the top of the trough-like portion 13. Also, the outer wall 30 is preferably almost in contact with the side wall of the pan. With the member 27 located in this manner, it will function properly. It will be rigidly held in position during operation of the machine. Rotation of the rod 25 will be precluded by the setscrew which is provided for securing it in position. Thus, the member 27 will always be maintained in proper relation to the pan.

The polishing material in the form of a fluid 20 or semi-fluid will lie in the trough-like portion 13, as previously stated. When the spindle 7 is rotated, the pan 8 and the lap 5 will also be rotated. The member 27 will remain stationary. Rotation of the pan causes the rouge to be thrown outwardly by centrifugal force against the side wall of the pan and to whirl around with the pan. Since the material is thrown outwardly against the side wall of the pan, the member 27 will scoop it in. The material will be forced into the pocket 39 and will build up considerable pressure therein. This pressure of the material will serve to force a portion of it through the narrow slot 36 into the chamber 31. Because the chamber 31 gradually decreases in cross sectional area, the pressure of the polishing material which will fill the chamber 31 will be increased as the material is forced towards the outlet opening 41. This material will be forced in a small stream under considerable pressure 40 through the tube 42 and out through the flexible tube 46 and onto the upper surface of the lap 5. The amount of material applied to the lap may be controlled by operation of the valve 43.

When rotation of the pan 8 is stopped, the material within the chamber 31 will automatically flow therefrom through the slot 36, due to the inclination of the bottom 32 of said chamber. Because the portion 39 of the bottom wall is cut off directly below the slot 36, emptying of the chamber 31 will be facilitated. Thus, as soon as the machine stops working, the chamber 31 will be automatically emptied so that there will be no danger of the polishing fluid drying and clogging up the device.

Because of the structure of the tool and the mounting therefor, it will not be necessary to change the vertical position of the member 27 each time a convex tool is removed and replaced by a concave tool or vice versa. The member 27 is so positioned that it will not contact with the wall of the pan and interfere with rotation thereof.

It will be apparent from the above that I have provided a novel means for mounting the tool on a machine of the type indicated and novel means for feeding the polishing or other abrasive material to the lap so that there will always be a sufficient supply for proper polishing or grinding of the lens blank. Furthermore, these two means have various advantages in themselves but also cooperate with each other in an advantageous manner.

It will be understood that when I refer to 75

"polishing material" or a "polishing machine" in the following claims, I intend to cover also other abrasive materials and lens grinding machines in general.

5 Having thus described my invention, what I claim is:

10 1. In a machine of the type described, a pan-like structure for receiving the abrasive or polishing material mounted for rotation, a lap, said lap having a projection on its lower surface adapted to fit within a socket formed in the bottom of said pan-like structure, an eccentric lock for maintaining said projection in said socket, and means for automatically picking up the 15 abrasive or polishing material in the pan-like structure and feeding it onto said lap.

20 2. In a machine of the type described, a lap, a lap carrier, and means for mounting said lap on said carrier, said means including an eccentric lock.

25 3. In a machine of the type described, a rotatable spindle, a lap, means for securing said lap to said spindle in such a manner that it will

rotate therewith, said means including an eccentric lock.

4. In a machine of the type described, a rotatable spindle, a pan-like structure for receiving the abrasive or polishing material, said pan-like structure being mounted on said rotatable spindle and being adapted to rotate therewith, a lap, and means for attaching said lap to the bottom of said pan-like structure, said means including an eccentric lock. 5

10 5. In a machine of the type described, a rotatable spindle having a tapered upper end, a pan-like structure for receiving the abrasive or polishing material having a tapered chuck adapted to fit over the tapered portion of the spindle, a 15 lap, means for mounting said lap on the bottom of said pan-like structure, said means including an annular depending flange formed on said lap, a socket formed in the bottom of said pan-like structure and adapted to receive said flange, 20 and an eccentric lock for tightly holding said flange within said socket.

LOWELL L. HOUCHIN.
